PROCESS OF AND APPARATUS FOR AIR
CONDITIONING

Joseph N. Hadjisky, Birmingham, Mich.

Application January 11, 1932, Serial No. 585,918

29 Claims. (Cl. 62—176)

This invention relates to air conditioning apparatus, and more particularly to an improved process for controlling the temperature and humidity of the air within a given space, by providing positive means for circulating such air, and means appurtenant the circulating apparatus for conditioning the air so circulated. Various systems and constructions have been employed in the past for accomplishing this purpose, which 5 systems, however, have had many inherent limitations, and have been so cumbersome and complicated as to prohibit their use in private homes, and to confine their use to auditoriums, large buildings, theaters, etc.

10 The system perhaps most commonly used incorporates positive air circulating means in connection with which a given portion of the air desired to be conditioned is treated in a single chamber, in which it is both cooled and dehumidified. In such a system the conditioning process is of course dependent upon accurate control of the temperature of the cooling medium, (usually cold water spray or combined spray and refrigeration). The only other system in common use 15 for accomplishing similar results provides a separate dehydrating chamber, in which is placed a moisture absorptive substance (frequently silica gel or the like) for removing moisture from the air, while the cooling is entirely performed in a 20 separate and usually second chamber incorporating refrigeration or cooled water coils, cold water spray or the like. This arrangement is necessarily even more elaborate than the system first mentioned, as two complete and separate dehumidifying systems must be provided, together 25 with means for driving the moisture from one while the other is working. Moreover, both these arrangements not only necessitate use of apparatus occupying more space than is available in the 30 ordinary home, but the close regulation of the temperature of the cooling medium, etc., necessary to be maintained, obliges the attendance of an engineer practically constantly, further adding to the expense and impracticality of installations of such types in places where economy or 35 space must be considered.

My improved process contemplates use of separate chambers for cooling and dehumidifying, the functions of which are interlocked and overlapping in operation, although they are controlled by independent humidity and temperature-responsive regulating means, or their equivalents. Both the temperature and humidity of the conditioned air discharged by such apparatus, when 40 operated in accordance with the principles of my

improved process, are relatively independent of variations of temperature of the cooling media in each chamber. The last statement requires the further explanatory observation that I preferably employ cooling coils for dehumidifying as well as 5 cooling. This latter feature assists in enabling incorporation of the process in apparatus of novel simplicity and compactness.

In order to illustrate the principles of my invention I have shown two constructions in which 10 the same are incorporated, but in which for purposes of clarity I have conformed, insofar as possible, to standard practice in the construction of air conditioning apparatus, varying therefrom only to the extent required to incorporate the 15 principles of my invention. The invention, however, insofar as the process is concerned will be seen to be entirely independent of the apparatus used.

From the foregoing brief résumé of the problems and conditions existing in the field here involved, it is believed that the primary objects and advantages of my invention may easily be gathered.

They may briefly be stated to be the provision of 20 a new system of air conditioning utilizing apparatus much simpler both in construction and operation than it has hitherto been possible to use.

A further object of my invention is the creation 25 of a novel degree of flexibility of operation in the conditioning process by controlling the degree of dehumidification and also the cooling process by varying the percentage of air treated in each chamber, independently of temperature variations of the cooling agent. Such arrangement allowing 30 the temperature of the cooling and dehumidifying agents to vary through a considerable range, creates important and valuable advantages which will become more apparent as the description progresses. The ability to control separately 35 and independently the temperature and the humidity of the zone served irrespective of temperature fluctuations of the cooling agent, enables achievement of flexibility heretofore altogether impossible.

A further object of my invention is the provision 40 of a system so simple that it may be incorporated in practical apparatus of very small size and low price, for home use or other uses where attendance of an operating engineer is not desirable.

A further object of my invention is the provision 45 of such an improved process, utilizable in conjunction with a supply of cooling water which may be at a temperature only slightly below that 50

desired for the conditioned air, thus frequently enabling use of a city or deep well water supply, for example, without necessitating artificial cooling thereof.

5 Other objects and advantages will be apparent from the following description, wherein reference is made to the accompanying drawings illustrating preferred embodiments of my invention, and wherein similar reference numerals designate 10 similar parts throughout the several views.

In the drawings:

Figure 1 is an isometric view of the exterior of one form of suitable apparatus embodying the principles of my invention;

15 Figure 2 is a vertical sectional view thereof taken substantially on the line 2—2 of Figure 1 and looking in the direction of the arrows;

Figure 3 is a vertical sectional view taken substantially at right angles to Figure 2 and on the 20 line 3—3 thereof, looking in the direction of the arrows;

Figure 4 is a plan view in partly horizontal section taken substantially on the plane 4—4 of Figure 5 and looking in the direction of the 25 arrows, showing a somewhat modified form of my invention, and

Figure 5 is a vertical sectional view thereof taken substantially on the line 5—5 of Figure 4, and looking in the direction of the arrows.

30 In carrying out my improved process I provide separate chambers for cooling and dehumidifying, in each of which a cooling agent is employed. In most air conditioning systems, as above stated, a single chamber is used for both cooling and 35 dehumidifying. Since dehumidification of such air as is usually desired to be conditioned cannot ordinarily be effected at any but relatively very low temperatures, usually requiring, if temperature difference is to be employed for dehumidification, a temperature of about 40° to 60° F. in the 40 dehumidifying chamber, it follows that if this same chamber is used for cooling as well, a waste- 45 age of refrigerating facilities results, from the necessity of reducing the entire chamber to the extremely low temperature required to accomplish dehumidification, whereas the cooling could just as well be done at a temperature difference of only a few degrees. By separating the cooling and dehumidifying processes to as great an extent as is possible, while yet using cooling media for both purposes, and by a novel system of control, I attain the above outlined results.

First considering the specific apparatus shown in Figures 1, 2 and 3, after a description of which 55 the process itself may be more readily understood: Reference character 1 designates the casing of one form of illustrative apparatus, which may, as shown, be embodied in a single housing. Air inlets 2—2' are provided in and adjacent the 60 bottom portions of its walls, one of which may, if desired be for re-circulated and the other for fresh air. As shown in Figure 2, the entering air is divided into three portions by partitions 5—5', which divide the interior of the housing directly 65 above the inlet chamber 3 into three sections, 6, 7 and 8.

The first of these (6) is a by-pass passage, through which air may be allowed to flow, untreated, directly to the circulating fans, by which 70 it is forced from the outlet. The by-pass is so arranged as to always allow the flowing therethrough of a quantity of air sufficient to provide a controlling balance which in regulated cooperation with the humidified and cooled air, the quantity 75 of which is subject to continuous control,

serves to regulate the conditioned output of the entire system in a manner which will subsequently be apparent. The remaining air passing through the device is distributed between the chambers 7 and 8.

5 The dehumidifying chamber 8 contains dehumidifying coils 9, which may constitute a portion of the evaporator system of a mechanical refrigerating apparatus connected thereto, as by means of couplings 9' provided on the outside 10 wall of the housing for such purpose. Since this chamber is smaller than the cooling chamber, and the air travel through it normally less, a relatively small refrigerating unit answers, although the coil 9 is best maintained at a relatively low 15 temperature. While the coil 9 serves to somewhat lower the temperature of the air flowing through the compartment 8, its principal function is that of dehumidifying such air. Air passing through this compartment is further dried 20 by the water droplet arrester 11, comprising a series of spaced substantially parallel crenelated vanes through which the air must pass and upon which any globules of moisture it may contain will be caught.

25 A relatively greater percentage of the total air flow through the conditioner is ordinarily passed through the larger cooling chamber 7, where the coils 10, which may be at a considerably higher temperature than the dehumidifying coils, perform a major portion of the cooling operation. The pipe lines leading to the cooling chamber may be run through the dehumidifying chamber to pre-cool the air entering the latter, or as shown in Figure 2, a portion of the tubes themselves may 30 be run through the dehumidifying chamber. These dehumidifying pre-cooling portions of the tubes are designated 10'.

35 A series of dampers 12—13 extends across the housing in such manner as to control the entire 40 air flow therethrough. The dampers 12 are arranged to control the flow of the air which has passed through the by-pass and cooling chambers 6—7, which air may mingle in the space 21 above them before flowing through the dampers. 45 The dampers 13, which control the air flow through the dehumidifying chamber 8, may as shown be connected to and controlled together with the same mechanism as the dampers 12, being so arranged that as the dampers 12 are moved 50 toward closed the dampers 13 are moved toward opened position, and vice versa. A lost motion connection is provided, or variant damper construction utilized, so arranged that when the dampers 13 are completely open, the dampers 12 55 are only partially closed. The details of the mechanism are of course immaterial inasmuch as my invention concerns primarily the process involved. The air which has passed through the dampers into the chamber 14 may be forced from 60 the outlet 18 by the fans 15, driven by an electric motor 16. The desired cooling of the coils 10 may be accomplished by cold water alone. The inlet and outlet couplings for this coil may also be mounted upon the exterior of the casing, as indicated at 10'.

65 The damper 4 controlling the by-pass passage may be directly controlled in response to the temperature changes in the area whose atmosphere is being conditioned, by means of a thermostat (not shown) directly connected to a bellows-operated or other suitable actuating mechanism 19 arranged to open the damper in response to a fall of temperature, and close it upon a rise of temperature, to force a greater 70 75 80 85 90 95 100

percentage of the air to pass through the cooling chamber.

The dampers 12-13 may be controlled by a hygrostat (not shown) also located in the zone 5 whose atmosphere is to be conditioned, and similar actuating mechanism 20 arranged to be responsive thereto. These dampers are so adjusted that upon a fall of humidity the dampers 13 tend to close and the dampers 12 to open, 10 so that a smaller percentage of the air passes through the dehumidifying chamber 8 and a greater percentage through the sections 6, 7, and vice versa.

It will be seen that by virtue of the automatic 15 control of the dampers 4-12-13 thus provided, the percentage of air by-passed, and that at any time passing through the cooling and dehumidifying sections, is constantly subjected to positive control which is entirely independent of 20 the temperature of the coils 9-10, and responsive only to conditions in the area served. Thus if the temperature in the served area tends to fall too low, the by-pass damper 4 is automatically opened, and a greater quantity of untreated air 25 allowed to flow therethrough, while variances in the humidity of the air in the controlled zone are also automatically compensated for by the dampers 12-13. A drip pan, as 3' may be employed and positioned, as shown in Figure 2, beneath the coils, to catch any condensed moisture which may fall therefrom. A drain pipe 30 3" is also shown, although these features are of course immaterial insofar as the invention is concerned.

35 This method of incorporating dehumidifying, cooling and by-pass passages entirely in one casing, and of varying in response to continuous automatic control the percentage of the total air flow which is permitted to pass through each 40 chamber, in response to conditions in the served area entirely, and independently of the temperature of the cooling and dehumidifying agents used in the apparatus, may be embodied in apparatus of various forms. The performance of 45 my improved system is further largely dependent upon the constant flow of at least some air through the by-pass, so that by direct and controlled variation of such flow independently of the remainder of the apparatus, the temperature 50 of the controlled air may be subjected to constant and simple control. Many variant but suitable forms of apparatus will doubtless suggest themselves to those skilled in the art.

55 A more detailed study of the effect upon the dehumidification and cooling processes of variations in temperature of the dehumidifying and cooling media, and an analysis of the total heat content balance as it is divided between the two chambers, will show both the independence of 60 the system's operation with respect to such variations, its flexibility, and the casual relation between the scientific control of the variables and the mathematical laws behind the process and the results which the process achieves.

65 An illustrative case will be considered to show the quantitative analysis of the passage of air through such an arrangement of apparatus as has been described in connection with Figures 1, 2 and 3. The calculations are made on the 70 basis of one pound of air as the unit amount handled and passed through the system. The heat and moisture loads are typical of a residence air conditioning problem. The given conditions 75 are as follows:

1. Temperature of air in inlet chamber 3	82° F.
2. Moisture content per pound of air in chamber 3	66 grains
3. Total heat per pound in air in chamber 3	5
4. Heat load to be removed per pound of air in chamber 3	29.6 B.t.u.
5. Moisture load to be removed per pound of air in chamber 3	3.3 B.t.u.
	3.9 grains 10

We will further assume the following required conditions:

1. Final moisture content per pound of air at outlet (18)	15
2. Total heat in air per pound delivered at outlet	26.3 B.t.u.
3. Final temperature of air leaving outlet (approx.)	70.5° F. 20

In the tabulated cases below I shall assume three different temperature conditions in the dehumidifying chamber, the temperature in the cooling chamber being assumed to remain constant. The weight of the air that will pass 25 through the dehumidification process can be found from the equation:

$$W_x = \frac{M_x}{M_3 - M_d} \text{ Pounds} \quad 30$$

Wherein

W_x = weight of air passing through dehumidifying chamber per pound of air delivered to entire system.

M_x = moisture load to be removed per pound of air (given) = 3.9 grains.

M_3 = moisture content per pound of supplied air (given) = 66 grains.

M_d = moisture content per pound of air leaving dehumidifying chamber. 40

See tabulated values below for each case.

Substituting in the equation, the following results are obtained:

Assumed cases	1	2	3	45
1. Dehumidifying chamber temperature, degrees F.	48	42.5	35	
2. Corresponding M_d (from standard tables)	50	40	30	
3. M_1 (given)	66	66	66	50
4. M_x (given)	3.9	3.9	3.9	
5. $M_3 - M_d$	16	26	36	
6. $W_x = \frac{M_x}{M_3 - M_d}$	.244	.150	.108	
7. W_x (percent)	24.4%	15.0%	10.8%	
8. Increase of W_x per one degree F. (average) =		1.1%		55

A study of these calculations discloses the fact that a random variation of temperature of the cooling agent of from 10° to 13° F. does not in any manner interfere with the dehumidifying process or its control. The relatively small proportion of the total treated air passing through the dehumidifying chamber (W_x) is shown by Item 6. Item 8 shows the relatively slight increase in the amount of air necessary to be passed through the dehumidifying chamber per degree rise in temperature. Comparison of the values shown in Items 4 and 5 makes plain the fact that it would require an abnormal increase in the value M_x to greatly affect in proportion to the volume of air treated, i.e., the value Item 6. 60

65

$$\left(\frac{M_x}{M_3 - M_d} \right)$$

In practice, such abnormal changes in the moisture load as those here contemplated do not occur. The variation of moisture load, expressed in grains per pound of air is ordinarily very gradual and slight from hour to hour.

Considering Item 6 from a somewhat different angle it will be seen that its maximum increase relatively to the whole pound of air handled is 14 per cent, but its absolute increase from 10 case 3 to case 1 is

$$\frac{.244 - .108}{.108} \times 100 = 133\%$$

I make use of this relationship to control the process in the dehumidifying chamber, and the relatively large "absolute variation" of the amount of air to be passed through the chamber makes possible the use of a damper to control the same, with the resultant simple and reliable operation characteristic of this means of control, especially where velocities, as here, are low. The process is thus regulated by the value W_x , while W_x in turn is controlled by a damper (13) responsive only to the variation of M_x in the served area, throughout wide variances in the temperature of the cooling agent.

Considering next the balance of the total heat content as it is divided between the cooling and dehumidifying chambers, it should be noted that 30 some heat is removed from the air in the dehumidifying chamber without a corresponding fall of temperature, in accordance with a well known law of thermodynamics. The relative quantity of air passing through the dehumidifying chamber is ordinarily less than through the cooling chamber, as above stated. A temperature drop is of course caused by the removal of heat from the air in this chamber, which heat is removed by condensation of moisture in the air, and some by cooling of the air itself. The total 40 heat removed may be expressed by the equation,

$$H_x = W_x (H_3 - H_d)$$

in which

45 H_x = B. t. u. removed by dehumidifier per pound of air delivered thereto,

W_x = weight of air passing through dehumidifying chamber per pound delivered to the entire system,

50 H_3 = total heat per pound in supplied air (given) = 29.6 B. t. u.

H_d = total heat per pound in air supplied to the dehumidifier.

55 Tabulating and calculating values for heat balance during dehumidification process in the three assumed cases:

Tabulation of calculated values for heat balance during dehumidification process

60	Cases	1	2	3
1. Dehumidifier chamber temperatures, degrees F.....	48	42.5	35	
65 2. W_x (from previous tables) in pounds.....	.244	.150	.108	
3. Heat load to be removed (given) B. t. u.....	3.3	3.3	3.3	
4. H_3 (given).....	29.6	29.6	29.6	
5. H_d (from standard tables).....	19.2	16.5	13.0	
6. $H_3 - H_d$	10.4	13.1	16.6	
7. $H_x = W_x (H_3 - H_d) = B. t. u.$	2.17	1.97	1.81	
8. Percent of heat load removed.....	65.7	59.8	54.9	
70 9. Percent of heat load left to be removed by cooling process.....	34.3	40.2	45.1	

Thus it is seen that in these assumed cases from 55 to 65 per cent of the total heat load is removed 75 by the dehumidifying chamber of the apparatus.

The exact percentage of heat which will be removed by the dehumidifier chamber is proportional to the relation of the sensible heat load to the latent heat load. This, however, is established by the conditions of each problem and cannot be changed very much. It is of course desirable to remove in the dehumidifying chamber as small a percentage of the total heat load as possible.

Examining the equation $H_x = W_x (H_3 - H_d)$, the next important factor, W_x , is also seen to be fixed by the moisture load. The only variables which can be utilized for the purpose of absorbing more of the heat with the coils 10 is to decrease H_3 in the equation $H_x = W_x (H_3 - H_d)$ or to increase H_d . 15 But as I have chosen to allow a random fluctuation of the temperature of the cooling medium in coils 9 from 35 to 48° F. for special purposes, H_3 is the logical and most effective item to be changed in its relation to the dehumidification chamber process. The means I have chosen to do this are the following: By extending part of coil 10 in chamber 7 through the lower part of chamber 8 the air going into the chamber 8 is pre-cooled. It can be shown by calculation that in this way 25 an amount of heat load from 12 to 30% of the total can be added to the cooling chamber coils 10. It should be noted that this latter is at a higher temperature level. Wherever cooling agents of different temperature levels are used such pre-cooling will give additional refrigeration economy.

The cooling process, which takes place in chamber 7 in the illustrative construction, is a relatively simpler problem when separated from the dehumidifying process. The calculations for the heat removal are made on the basis of the balance of total heat load left after deducting the dehumidifier heat balance from the results arrived at in the preceding tabulation.

Tabulated values for heat exchange in cooling chamber under assumed conditions

Cases	1	2	3	45
1. Total heat load (given) B. t. u.....	3.3	3.3	3.3	
2. Heat load removed by dehumidifier.....	2.17	1.97	1.81	
3. Remaining heat load to be removed by cooling process.....	1.13	1.33	1.49	
4. Maximum weight of air capable of passing through cooling chamber per pound circulated.....	.756	.850	.892	50
5. Temperature of air in chamber 3, given, degrees F.....	82	82	82	
6. Temperature drop if all air in Item 4 is cooled.....	6.3	6.6	7.05	
7. Temperature drop if 75% of such air is cooled.....	8.4	8.85	9.36	55
8. Temperature of air leaving cooler if 75% goes through, degrees F.....	73.6	73.15	72.64	
9. Temperature of air leaving cooler if 50% goes through, degrees F.....	71.5	71	70	

Items 6 and 7 show the relatively small temperature drop required to perform the cooling operation. The second result of importance will be noted from a study of Items 8 and 9. Comparing the final temperature here with the final temperature in the dehumidifying chamber it will be seen that there is a difference of about 30° F. The cooling process can thus be carried on with a cooling agent at a much higher temperature than is required in the dehumidifying chamber. This temperature difference will be seen to represent 60 pure gain insofar as economy of operation is concerned, since it is unnecessary to provide refrigerating means at the relatively greatly reduced temperature used in the dehumidifying chamber. In the cooling chamber it is usually 65 70 75

possible to employ city water as the cooling medium rather than artificial refrigeration; at, of course, a considerable saving of expense, since such cooling water is used to remove about half the entire heat load, whereas in the processes heretofore used it has been necessary to use artificially-cooled means for removing the entire heat load. Even if artificial refrigeration is also used to reduce the temperature of the cooling 10 chamber, a considerable saving in expense of operation results from the employment of my improved process, since carrying this chamber at a relatively high temperature (perhaps 60° F.) permits employing more economical and compact refrigerating apparatus. Perfect results can also be obtained by the use of ice cooled water in the dehumidifying chamber and city water for the cooler, thus dispensing with artificial refrigeration entirely.

20 A consideration of Items 4, 6 and 7 shows that there may be considerable variation in the amount of air passing through the cooling chamber. I make use of this fact to further control the process by controlling this factor, rather than controlling the temperature of the cooling agent as is the common practice.

Another suitable arrangement of apparatus for carrying out my improved process is shown in Figures 4 and 5, in which is shown a construction whereby the air is first permitted to flow through the by-pass and cooling chambers, after which a regulatable and variable portion of the entire flow passes through the dehumidifying chamber 108. In this construction, in which analogous parts to those described in connection with the first mechanical embodiment have been given similar reference numerals one hundred integers higher, the dampers 112—113 may be similarly controllable and reversibly operable, under the influence of the humidity-responsive actuating member 120. Similar lost motion connection between the dampers is also preferably provided. The by-pass dampers 104 are connected to the temperature-responsive controlling member 119, 45 and thus regulate the percentage of air which is forced to pass through the cooling chamber 107. Separate refrigerating units 122—123 may be used for cooling the coils 109—110, with the benefits of economy previously outlined resulting from the elimination of the necessity of performing the cooling by means of coils maintained at low temperature or if desired, cold water spray may be utilized in the dehumidifying chamber, as shown in Figures 4 and 5. In these views the nozzle-carrying spray pipes are designated 109, the coupling means for connecting the cold water lines thereto, 109'. Whatever the cooling agent utilized in the dehumidifying chamber, the more greatly reduced temperature need be maintained 50 only therein, while the cooling chamber may be operated at the higher temperature made possible by my improved process, thus obtaining the above outlined inherent economies.

While it will be apparent that the illustrated 65 embodiments of my invention herein disclosed are well calculated to adequately fulfill the objects and advantages primarily set forth, it is to be understood that the invention is susceptible to variation, modification and change within the 70 spirit and scope of the subjoined claims.

What I claim is:

1. In an air conditioning apparatus, separate 75 chambers through which air to be conditioned is adapted to flow, in one of which humidity correction is the paramount consideration, and in an-

other of which temperature correction is intended to be effected, and means for controlling the functioning of the apparatus, comprising interlocked damper means for controlling the flow through each such chamber, so arranged that by 5 continuous movement such damper means may be made to effect opening movement of one and closing movement of the other.

2. In an air conditioning apparatus, separate 10 chambers through which air is adapted to flow, in one of which humidity correction is the primary consideration, in another of which principally temperature correction is effected, and through another of which untreated air may pass, and means for controlling the functioning of the apparatus, comprising humidity-responsive damper means for interdependent controlling of the proportion of treated air passed through the dehumidifying chamber and that passed through the remaining portions of the apparatus, one being adapted to be moved toward opened and the other toward closed position by continuing movement of said damper means, and additional damper means, responsive only to the temperature in the 15 served area, for controlling the proportion of air by-passed.

3. In an air conditioning apparatus incorporating separate chambers, a cooling coil within one chamber adapted primarily for cooling, a second cooling coil at a relatively lower temperature than the first, arranged within another chamber and primarily intended for dehumidification, a portion connected to the first mentioned coil being extended through the second chamber in a manner adapted to pre-cool the air passing therethrough.

4. The process of cooling and dehumidifying air which includes circulating the air desired to be conditioned, dividing the air so circulated, changing the humidity of one such divided portion, concurrently separately changing the temperature of another divided portion of the air, concurrently by-passing another divided portion, varying the proportion of the air passed thru the humidity-changing medium in response to humidity conditions in the conditioned zone, varying the volumetric proportioning of air between the by-pass and the temperature controlling medium in response to thermal conditions in the served zone, and recombining the portions of air so treated.

5. The process of cooling and dehumidifying air which includes circulating the air desired to be conditioned, dividing into separate portions the air so circulated, concurrently varying the 55 humidity of one such divided portion and the temperature of another, controlling the air flow thru the humidity varying section in response to humidity conditions in the conditioned zone, concurrently by-passing another portion of the air 60 around the temperature corrective section and separately controlling the air flow thru the by-pass in response to temperature conditions in the conditioned zone.

6. The process of cooling and dehumidifying air which includes circulating air from and to the area desired to be conditioned, dividing into separate portions the air so circulated, varying the humidity of one such divided portion in the desired direction by absorbing heat therefrom, concurrently separately varying the temperature of another such divided portion in the desired direction, so controlling the proportion of the total air flow thru the humidity varying section 70 in response to humidity conditions in the served 75

zone and the proportion of the total air flow thru the temperature varying section in response to temperature conditions in the served zone as to provide corrective adjustment of the humidity and 5 temperature of the conditioned air relatively independently of reasonable temperature variations of the corrective agencies.

7. The process of cooling and dehumidifying air which includes circulating air from and to 10 the area whose air is desired to be conditioned, dividing into separate portions the air so circulated, varying the humidity of one such divided portion, concurrently separately varying the temperature of another such divided portion, varying 15 apportioning the quantity of air passing thru each in response to humidity and temperature conditions respectively in the served zone, concurrently permitting another divided portion of the air stream to pass untreated, and controlling 20 the volumetric portion of the circulating air so by-passed also in response to temperature variations in the served zone.

8. The process of cooling and dehumidifying air which includes maintaining a refrigerating 25 agency for temperature correction at a temperature below that of the air to be conditioned, maintaining a humidity corrective agency at a relatively lower temperature, concurrently causing circulation of separate air streams through each 30 such agency, and controllingly apportioning the quantity of air permitted to flow thru each in response to temperature and humidity conditions in the area whose air is desired to be conditioned.

9. In air cooling and dehumidifying apparatus, 35 a cooling agency at a lower temperature than the air desired to be cooled, thru which such air may circulate, a dehumidifying agency at a more greatly reduced temperature and thru which air may be passed, damper means for controlling the 40 volume of air passing thru each agency, means for so controlling the damper in response to humidity variations in the served zone as to maintain one agency open to the passage of air while restricting the other, and vice versa, a by-pass 45 around the temperature corrective agency, and means for controlling the air flow thru the by-pass in response to variations of temperature in the served zone.

10. In an air cooling and dehumidifying system 50 having an inlet and an outlet, an air cooling agency at a reduced temperature relatively to the air to be treated, a dehumidifying agency at a lower temperature, means for conducting air over each agency, a portion of the cooling agency 55 being placed in advance of the dehumidifying agency so that air passes thru them in the order named and is pre-cooled by the cooling agency before entering the dehumidifying agency, a by-pass for conducting air from the inlet to the outlet 60 let without passing it through either agency, temperature responsive controlling means for the by-pass, and humidity responsive controlling means whereby the flow through the dehumidifying agency may be regulated.

65 11. The process of conditioning air which includes providing a cooling agency at a reduced temperature, and a dehumidifying agency at a lower temperature, and passing a portion of the air to be treated thru each and a portion thru 70 neither, but passing the air supplied to the dehumidifying agency first thru the cooling agency to be there pre-cooled, and regulating the air by-passed and passed through each agency in response to changes in temperature and humidity 75 in a served zone.

12. The process of conditioning air which includes providing a cooling agency at a reduced temperature, and a dehumidifying agency at a reduced temperature and a dehumidifying agency at a lower temperature, passing a portion of the air thru the cooling section, by-passing a portion therearound, and passing part of the pre-cooled air thru the dehumidifying agency, and controlling the proportion of air by-passed and passed through said agencies in response to temperature 10 and humidity conditions in a served zone. 5

13. The process of cooling and dehumidifying air which includes forming the air to be conditioned into a flowing stream, passing a portion of the stream through a temperature corrective 15 medium operating by temperature differential, passing another portion of the stream through a humidity corrective medium which also acts by temperature differential, and delivering the stream portions so treated to a served zone. 20

14. The process of cooling and dehumidifying air which includes forming the air to be conditioned into a flowing stream, passing a portion of the stream through a temperature corrective medium acting by temperature differential and 25 which is held at a temperature below that of the air to be conditioned, passing another portion of the stream through a similarly acting humidity corrective medium held at a still lower temperature, and delivering the stream portions so 30 treated to a served zone.

15. The process of cooling and dehumidifying air which includes forming the air to be conditioned into a flowing stream, passing a portion of the stream through a temperature corrective 35 agency at a temperature below that of the air to be conditioned, passing a portion of said stream through a humidity corrective agency acting by temperature differential and held at a lower temperature than said first mentioned agency, controllingly varying the percentage of the total air 40 flow passed through each agency, and delivering the stream portions so treated to a served zone. 45

16. The process of cooling and dehumidifying air which includes forming the air to be conditioned into a flowing stream, passing a portion of the stream through a temperature corrective agency at a temperature below that of the air to be conditioned, passing a portion of said stream through a humidity corrective agency acting by 50 temperature differential and held at a lower temperature than said first mentioned agency, by-passing a portion of the air untreated past both agencies, and controllingly apportioning the quantities of air by-passed and permitted to flow 55 through each agency.

17. The process of cooling and dehumidifying air which includes forming the air to be conditioned into a flowing stream, passing a portion of the stream through a temperature corrective 60 agency at a temperature below that of the air to be conditioned, passing a portion of said stream through a humidity corrective agency acting by temperature differential and held at a lower temperature than said first mentioned 65 agency, by-passing a portion of the air untreated past both agencies, controllingly apportioning the proportion of air by-passed in response to temperature conditions in the served area, and similarly controlling the proportion of flow 70 through each of said agencies in response to hygrostatic conditions in said area.

18. The process of dehumidifying air which comprises maintaining a refrigerating agency at a reduced temperature, and varying the quantity 75

of air permitted to pass therethrough in accordance with the equation

$$W_x = \frac{M_x}{M_3 - M_d}$$

- 5 19. The process of cooling and dehumidifying air which includes maintaining two separate refrigerating media at reduced temperatures but one at a lower temperature than the other, passing 10 air desired to be dehumidified through said lower temperatured medium, passing air desired to be cooled but not dehumidified through the other medium, controlling the proportion of the air passed through the dehumidifying medium 15 in response to changes of humidity in a served zone, and controlling the proportion of air passed through the cooling medium in accordance with a quantity of heat remaining to be removed, considering the proportional quantity thereof removed by the dehumidifying medium.
- 20 20. The process of conditioning air which includes maintaining separate cooling and dehumidifying media at reduced temperatures with respect to the air desired to be conditioned, but holding the dehumidifying medium at a lower temperature than the cooling medium, circulating such air through both media, and controlling the apportionment of the air allowed to flow through the cooling medium in accordance with the percentage of heat remaining unremoved by the dehumidifying medium, as expressed by the equation $H_x = W_x(H_3 - H_d)$.

- 35 21. The process of cooling and dehumidifying air which includes maintaining a refrigerating agency for temperature correction at a temperature below that of the air to be conditioned, maintaining another refrigerating agency for humidity correction at a still lower temperature, causing circulation of air through each of said agencies, 40 by-passing another portion of air untreated, controllingly varying the air flow through the humidity corrective agency in response to changes of humidity conditions only, and controllingly varying the by-passed air in response to temperature conditions only.

- 45 22. In an air cooling and dehumidifying system having an inlet and an outlet, an air cooling agency at a reduced temperature relatively to the air to be treated, a dehumidifying agency at a lower temperature, means for conducting air 50 over each agency, a portion of the cooling agency being placed in advance of the dehumidifying agency so that air passes through them in the order named and is pre-cooled by the cooling agency before entering the dehumidifying agency, and humidity responsive controlling means for regulating the flow through both the cooling and dehumidifying agencies.

- 55 23. In an air cooling and dehumidifying system having an inlet and an outlet, an air cooling agency at a reduced temperature relatively to the air to be treated, a dehumidifying agency at a lower temperature, means for conducting air over each agency, a portion of the cooling agency being placed in advance of the dehumidifying agency so that air passes through them in the order named and is pre-cooled by the cooling agency before entering the dehumidifying agency, and humidity responsive controlling means for regulating airflow within the system.

- 60 24. The process of cooling and dehumidifying air which comprises causing air, which is to be conditioned, to circulate in heat exchange relation with cooling surfaces to remove principally sen-

sible heat from the air when the relative humidity of the air to be conditioned is below a predetermined percentage, causing air, which is to be conditioned, to circulate in heat exchange relation with colder cooling surfaces when the relative humidity of the air to be conditioned is above a predetermined percentage, the temperature of which colder surfaces causes the air flowing thereover to be cooled to below the dew point thereof, and controlling the flow of air over the heat exchange surfaces in accordance with the relative humidity of the air to be conditioned.

65 25. The process of cooling and dehumidifying air which comprises causing air, which is to be conditioned, to circulate in heat exchange relation with cooling surfaces to remove principally sensible heat from the air when the relative humidity of the air to be conditioned is below a predetermined percentage, causing at least a part of such air to circulate also in heat exchange relation with other cooling surfaces when the relative humidity of the air to be conditioned is above a predetermined percentage, the temperature of which latter surfaces causes the air flowing thereover to be cooled to below the dew point thereof, and controlling the flow of air over the heat exchange surfaces in accordance with the relative humidity of the air to be conditioned.

70 26. An air conditioning system comprising, in combination, a heat absorber, the main function of which is to remove principally sensible heat from air flowing thereover, a second heat absorber adapted to cool air flowing thereover to below the dew point thereof, means for controlling the flow of air over the second mentioned heat absorber, and means responsive to the relative humidity of the air to be conditioned for actuating the controlling means.

75 27. An air conditioning system comprising, in combination, a heat absorber, the main function of which is to remove principally sensible heat from air flowing thereover, a second heat absorber adapted to cool at least a part of said air to below the dew point thereof, means for controlling the flow of air over the second mentioned heat absorber, and means responsive to the relative humidity of the air to be conditioned for actuating the controlling means.

80 28. An air conditioning system comprising, in combination, refrigerating apparatus including an evaporator, the main function of which is to remove principally sensible heat from air flowing thereover, a second evaporator adapted to cool air flowing thereover to below the dew point thereof, means for controlling the flow of air over the second mentioned evaporator, and means responsive to the relative humidity of the air to be conditioned for actuating the controlling means.

85 29. A conditioner unit for air conditioning systems including a pair of chambers arranged in parallel, one chamber constituting an air cooler for absorbing latent heat from the air stream passing through it, the other chamber having cooling means therein for absorbing substantially only excess sensible heat of the air passing through it, means for delivering an air stream to be conditioned to the inlets of said chambers and for proportioning the amount of the stream which passes through the two chambers, means whereby the divided portions of the air stream commingle after leaving the chambers.

JOSEPH N. HADJISKY.
